UNITED STATES PATENT OFFICE.

LOUIS A. EPPENSTEIN, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A WATCHCASE.

Application filed January 18, 1926. Serial No. 16,154. Term of patent 3½ years.

To all whom it may concern:

Be it known that I, LOUIS A. EPPENSTEIN, a citizen of the United States, residing at Elgin, in the county of Kane and State of Illinois, have invented a certain new, original, and ornamental Design for Watchcases, of which the following is a specification, reference being had to the accompanying drawing, forming part hereof, wherein—

Figure 1 is a plan view, and Fig. 2 an edge view, of a watchcase showing my new design.

I claim:

The ornamental design for a watchcase as shown.

LOUIS A. EPPENSTEIN.
